UNITED STATES PATENT OFFICE.

SAMUEL STRAUSS, OF LOS ANGELES, CALIFORNIA.

METHOD OF MAKING SHOES.

1,221,388.

Specification of Letters Patent.

Patented Apr. 3, 1917.

Application filed July 12, 1915. Serial No. 35,248.

To all whom it may concern:

Be it known that I, SAMUEL STRAUSS, a citizen of the United States, residing at Los Angeles, in the county of Los Angeles and 5 State of California, have invented a new and useful Method of Making Shoes, of which the following is a specification.

An object of this invention is to produce a shoe by a method whereby maximum simplicity and cheapness of production are attained.

Another object is to produce a shoe that will have absolutely no seams on the inside of the shoe so as to afford maximum comfort to the wearer.

Another object is to effect a saving in the number of dies and lasts required to manufacture a line of shoes of different styles and sizes.

20 Another object is to maximize the ease of sewing the sole and upper together.

Another object is to effect the sewing in a way that will insure that the stitches are made in a path conforming to the shape of 25 the last.

Another object is to so produce a shoe that the upper thereof will be held in shape, even though said upper is made of very soft and pliable material such as rubber or cloth.

30 The accompanying drawings illustrate the invention:

Figure 1 is a vertical section of a machine capable of carrying out a portion of the improved method and of partly making the improved shoe.

Fig. 2 is a longitudinal mid section through the upper formed by the machine shown in Fig. 1, a last and a sole also being shown in position for sewing together.

40 Fig. 3 is a longitudinal mid section of the same upper, sole and last illustrating the basting operation, the basting ring and lasting collar also being shown.

Fig. 4 is a longitudinal mid section of the 45 upper, sole and last with the basting ring removed, the upper and sole being stitched together.

Fig. 5 is a longitudinal mid section of the completed shoe.

50 Fig. 6 is a plan view of the shaper or lasting collar shown in Figs. 3 and 4.

Fig. 7 is a longitudinal section of a shoe provided with the improved stiffening band.

The machine for carrying out part of the 55 process by which the novel shoe a, Fig. 5 is made is provided with a base 1 having

mounted thereon a female die 2 and having guides in the form of round rods 3 fixed therein and projecting upward from said base. On the rods 3 is shiftably mounted a follower 4, and said follower is resiliently supported by coil springs 5 surrounding the rods 3 between the base 1 and ears 6 of the follower, said ears being perforated to accommodate the rods 3.

The follower is provided with perforations 7 to accommodate rods 8 carrying at their lower ends a presser member or foot 9, there being coil springs 10 surrounding the rods 8 between the ears 6 and presser foot 79 to normally depress the presser foot toward the female die 2.

The follower 4 is provided with recesses 11 in which are mounted spring sockets 12 designed to detachably engage buttons 13 75 projecting from the upper face of a male die or last 14 that is designed to be forced into the mold cavity 15 in the die 2 by pressure exerted on the follower 4, said pressure being produced by any desired means or mechanism or system of levers, not shown.

The base 1 may be provided with a recess 16 designed to receive an ejector 17 normally pressed upward toward the die 14 by a coil spring 18 seated between the ejector 85 and bottom of the recess.

To effect the first step in the novel method of making a shoe in accordance with this invention, the follower 4 and its die 14 will be raised and the presser foot 9 will also be raised and a piece of leather 19 will be soaked in water to render it more pliable and said leather will then be laid on the flat flange 20 of the die 2.

Then the presser foot 9 will be allowed to descend and engage said leather 19 to securely hold the same in position on the die 2. Then the follower 4 will be operated to move the die 14 downward to press the leather 19 into the mold cavity 15 to make an upper 21 of a shoe of the desired shape and approximate size having an outwardly extending flange 22, thus completing the first step of the method.

The other steps of the process will then be performed as follows: The follower 4 and die 14 will be raised, thus allowing the ejector 17 to operate to eject the upper 21 from the mold cavity 15. A piece of sole leather 23 will then be fastened by 105 nails 24, or the like, to a last 25 of wood or other suitable material, and said last will

be inserted in the upper 21 with the sole resting in contact or substantially in contact with the outturned flange 22 of the upper as in Fig. 2.

5 Then a shaper or lasting collar 26 of hard fiber or the like will be placed around the upper 21 and in contact with the upper surface of the flange 22, and a basting ring 27 preferably of metal will be placed around the upper and against the lasting collar.

10 The pressure ring 27 is connected by any suitable means to any suitable source of power and in the instance shown said means comprises links 28 hinged at 29 to the ring 27 and provided with straps 30 which may be pulled upon by the operator to produce the desired amount of pressure of the ring 27 against the lasting collar.

15 The lasting collar 26 gives the exact size 20 to the shoe, and several such collars of different sizes are used with a single size of last, the last only giving the approximate size to the shoe.

20 Pressure is applied to the ring 27 to force 25 the collar 26 toward the sole 23 so as to draw the lower part of the upper toward the last to give said upper the exact shape and size determined by the size of said collar and to securely hold the sole and flange 22 in close contact with one another, and said sole and flange will then be basted together by nails 31 or equivalent driven through holes 32 extending through the ring 27, as in Fig. 3, said holes being of larger 35 diameter than the nails.

25 Then the basting ring 27 will be removed, the nails 31 securely holding the sole and upper together. Then the upper 21 with the last 25 therein and the lasting collar 26 fastened in place will be sewed either by hand or by machine so as to form stitches 33 entirely around the lower part of the upper through the flange 22 and sole 23 between the lasting collar 26 and the portion 40 of the upper that is adjacent the flange so as to fasten the sole 23 and upper firmly together as in Fig. 4.

30 Then the top portion 34 of the upper will be cut away to form the opening 35 and said upper will be slit at 36 from said opening toward the toe, and then the lasting collar 26 will be ripped off and the flange 22 and sole 23 will be trimmed in the usual way by any suitable means, sufficient of the flange 35 being allowed to remain on the upper to securely hold the stitches 33 to form a tight joint between the upper and the sole and to form a so-termed extension. The last 25 is then removed through the opening 35 and slit 36. If desired a heel 37 may be added.

35 This completes the shoe shown at *a*; Fig. 5. From the foregoing it is seen that several uppers of, for instance, sizes Nos. three, four and five, can be formed by dies and last of

40 No. four size and lasting collars of Nos.

three, four and five sizes, thus saving the expense of two dies and two lasts. Also any shape of shoe can be made by this method irrespective of the style of die used, for the shoe can be made to conform to the desired 70 style of last by employment of the lasting collar 26. It is noted that by this method the soling, sewing and trimming operations may be effected while the upper is still wet, the lasting collar 26 and flange 22 holding 75 the upper in shape while said operations are being made, thereby minimizing the number of lasts necessary to use in the manufacture of a given number of shoes, at least fifty per cent. being saved in the number of 80 lasts required as it is not necessary to wait until the uppers are dry before releasing the lasts therefrom. It is obvious from this that shoes may be made by this method in much less time than by methods heretofore known. 85

The lasting collar 26 may be used over and over again and is reversible so as to be adapted for right and left shoes and said collar, in the operation of sewing the sole 23 to the upper, guides the sewing needle so 90 as to maximize the ease of sewing and greatly facilitate forming the stitches in a path conforming to the shape of the last.

It may be desirable in some instances to thicken the extension so as to better hold 95 the upper in shape, especially when the upper is made of very soft or flimsy material, and to do so a flat band 38 about the same width as the flange 22 will be basted on top of said flange between the lasting collar 26 100 and the marginal portion of the sole 23 and the shoe will be sewed with stitches 39 as in Fig. 7 extending through said band, flange and sole to hold them all firmly together.

From the foregoing it is clear that by my 105 method shoes can be made in very much less time than heretofore and the shoes thus made are provided with absolutely no seams inside thereof to cause discomfort to the wearer, and I am not aware that a shoe of 110 this description has ever been invented.

I claim:

1. The method of making shoes, which method comprises soaking a piece of leather in water to make it pliable, applying forming dies to the wet leather to shape it into an upper having an outturned flange, inserting a last inside of said upper while said upper is wet, basting a sole to the flange and the flange to a collar while the upper is wet, stitching the flange and sole together around the inner edge of said collar while the upper is wet, removing the last from the upper, allowing the upper to dry out, and then ripping off the collar. 115 120 125

2. The method of making shoes, which method comprises soaking a piece of leather in water to make it pliable, applying forming dies to the wet leather to shape it into an upper having an outturned flange, insert- 130

ing a last inside of said upper while said upper is wet, placing a band of stiff material on the top surface of the flange, basting a sole to the flange and the flange to the band 5 and said band to a collar to hold them all together, stitching the flange and sole and band together around the inner edge of said collar, removing the last from the upper, allowing the upper to dry out, and then 10 ripping off the collar.

3. The method of making shoes, which method comprises inserting a last into an upper having an outturned flange, drawing a collar over the upper against said flange, 15 basting the collar and flange and a sole together, stitching the flange and sole together, removing the last, and finally removing the collar.

4. The method of making shoes, which 20 method comprises soaking a piece of leather in water to make it pliable, applying forming dies to the wet leather to shape it into an upper having an outturned flange, inserting a last inside of said upper while said 25 upper is wet, basting a sole to the flange

while the upper is wet, stitching the flange and sole together while the upper is wet, and finally removing the last from the upper.

5. The method of making shoes, which method comprises soaking a piece of leather 30 in water to make it pliable, holding the marginal portions of said piece of leather, pressing out the central portion of said piece of leather to form an upper and to form a flange outturned from said upper, fastening 35 a piece of sole leather to a last, inserting said last in the upper thus pressed out so that the sole leather will extend in proximity to the outturned flange, fastening the sole to said flange, cutting said upper to make an opening 40 therein, and then removing the last through said opening.

In testimony whereof, I have hereunto set my hand at Los Angeles California this 3rd day of July 1918.

SAMUEL STRAUSS.
